Atty.

UNITED STATES PATENT OFFICE.

WILLIAM A. MASON, OF BOSTON, MASSACHUSETTS.

BENCH FOR HANDLING OIL-BURNERS.

1,395,856.

Specification of Letters Patent. Patented Nov. 1, 1921.

Application filed March 19, 1920. Serial No. 367,280. Renewed September 12, 1921. Serial No. 500,267.

To all whom it may concern:

Be it known that I, WILLIAM A. MASON, a citizen of the United States, residing at Boston, in the State of Massachusetts, have 5 invented certain new and useful Improvements in Benches for Handling Oil-Burners, of which the following is a specification.

My invention relates to means for manipulating burners for oil burning furnaces 10 of what are called the atomizer type.

These oil burners are commonly used on steam vessels and power plants generally and they consist of an elongated pipe adapted to be connected and disconnected with the 15 source of supply and having at the discharge end a plug or tip containing a very small hole in some cases as small as .005 inch in diameter. The plug which carries the hole is adapted to screw onto the end of the nozzle or pipe and on account of its size it is liable to become clogged from the dirt contained in the oil.

The instant the perforated tip plugs up there is nothing to be done but to remove 25 the burner and put in a new one, a number of spare burners being kept on hand at all times. As soon as the burner is removed the tip must be unscrewed from the end and cleaned. The ordinary method is to hold 30 the pipe in a vise to keep it from rotating and then unscrew the tip. When this method is used it is not infrequent that the burner pipe may be cracked causing a leakage of oil.

Again, the burner when removed is filled 35 with oil and this oil is spilled on the floor or on the bench making a disorderly condition in the boiler room.

According to my invention I provide a 40 bench upon which the burner may be laid immediately it is removed, with a jaw at one end into which the portions of the burner next the tip falls and there held from rotating. The rear end of the burner 45 rests on a support on the rear end of the bench allowing the disconnecting end of the burner to overhang a drip pan containing an opening beneath which is a vessel for catching the surplus oil. The rear rest is so located 50 that it gives a little rearward pitch to the burner and thus drains off the oil while the tip is being removed and cleaned.

The bench contains two laterally extending partitions having recesses in their upper

edges so that a number of spare nozzles may 55 be laid side by side to remain until wanted.

I have illustrated my invention by means of the accompanying drawing in which I show a bench constructed in accordance with 60 my invention.

In the drawing:

Figure 1 is a side elevation of the bench with one of the burners in position to be taken apart and cleaned.

Fig. 2 is a plan of the same and, 65

Fig. 3 is an end elevation.

The bench is made up of uprights 1 and horizontal members 2 and 3 so that it stands firmly on four legs.

The upper portion is made with a horizontal floor divided by a partition 7 into two flat pans or trays 5 and 6. The pan or tray 6 has an opening 8 for drainage and beneath the opening is a ledge or floor on which a bucket 9 may be placed to catch the 75 oil which drips from the end of the nozzle.

The burners are of various forms and vary more or less but they all consist of a straight pipe 12 with a tip 13 at the discharge end, this tip or cap being screwed to the end of 80 the pipe 12. On the rear end of the pipe is the fitting 14 by which the nozzle is connected to the source of oil supply. At one end of the bench is located a fixed jaw 11 adapted to hold the body of the burner from 85 turning when the tip is being removed. The "Ferris" burner here shown has a hexagonal portion just back of the tip and this is easily held in the jaw 11 and holds the pipe from rotating while the tip is being unscrewed. In other forms of burners the pipe is round at this point. The fixed jaw 90 I prefer to make V-shaped with teeth that will seize and hold a round pipe or a hexagonal or other like surface.

In order to hold the pipe more securely where a round surface is held I provide a pivoted jaw 15 which has a serrated recess 16 adapted to shut down over the burner pipe and hold it when an unusual strain is 100 put on it.

The rear end of the burner rests in a recess in the cross partition 7 which is so placed that the nozzle will incline rearwardly. The oil will thus all drain out and 105 drip into the pan or tray 6 and passing through the opening 8 fall into the bucket 9. The partition 7 and a similar partition 18

on the front end of the bench have recesses in which several burners may be placed after they have been taken apart and drained as shown in Fig. 2.

5 The fixed jaw 11 is secured in place by bolts 17 passing through slots so that the height of the jaws may be varied to provide the proper pitch for the burner.

The device is set up in the boiler room 10 of the steamer or plant using oil and by its use the burner may be quickly taken apart and cleaned and without any danger of cracking the pipe or causing a leak which sometimes happens when the old method 15 is used.

I claim:

1. A bench for manipulating oil burners of the class described having a jaw at one

end to prevent the burner from turning, a support near the other end of the bench 20 lower than said jaw to allow the oil to drain out of the burner and a tray positioned to receive the drainage, said tray having an outlet opening adapted to coöperate with a receiving vessel.

2. A bench for manipulating oil burners of the class described having a jaw at one end to prevent the burner from rotating, a transverse partition extending across the bench, said partition having recesses in its 30 upper edge to retain a plurality of burners and an oil receiving pan for catching the drip from said burners.

In testimony whereof I have affixed my signature.

WILLIAM A. MASON.
